(57) **CLAIM**

The ornamental design for the outdoor lighting fixture, as shown and described.

DESCRIPTION

FIG. 1 is a perspective view of an outdoor lighting fixture as seen from above according to my new design.

FIG. 2 is a perspective view thereof as seen from below.

FIG. 3 is a right side elevational view thereof.

FIG. 4 is a left side elevational view thereof.

FIG. 5 is a front elevational view thereof.

FIG. 6 is a rear elevational view thereof.

FIG. 7 is a top plan view thereof; and,

FIG. 8 is a bottom plan view thereof.

The broken lines shown on the drawings depict portions of the outdoor lighting fixture that form no part of the claimed design.
